OVERHEAD CARRIAGE STOP DEVICE MOUNTED UPON A BEAM ALONG WHICH THE CARRIAGE TRAVELS William R. Schriver, 1278 Saxonburg Blvd.,
Glenshaw, Pa.

Filed Feb. 6, 1959, Ser. No. 791,564

12 Claims. (Cl. 104—98)

This invention relates to a stop device mounted upon a beam along which an overhead crane or carriage travels from one beam to a second beam disposed in an abutting end to end relationship. It is especially adapted for beams, rails or tracks which support overhead cranes, hoisting devices, etc. which travel along the tracks or rails from one beam to another.

In a number of buildings, warehouses, industrial plants, etc. where overhead cranes lift and transport goods from one station to another station, the overhead crane travels from one track or rail to a second track or rail in order to move the goods. Such travel is often effected by use of a movable or floating track or set of tracks onto which the crane is moved from a fixed track or rail. To bring about the travel, it is necessary that the movable or floating rail be brought in an end to end relationship with the fixed rail and be aligned therewith. Unless there is proper alignment of the movable rail with the fixed rail, cranes either cannot be transferred or if transferred, may be derailed in the transfer and/or drop their load or cause it to shift to an awkward and untransportable position.

Until the alignment of the rails in the end to end relationship is completed, it is essential that the crane cannot run off the track on which it rides. Thus it is highly important to provide a dependable and foolproof stop which prevents such run-off or derailment until the alignment is completed and which stop cannot be inadvertently opened or withdrawn from a position whereat it intercepts the crane and prevents travel off of its track.

I have invented a stop device for rails or tracks along which an overhead crane or carriage rides. My stop device cannot be inadvertently withdrawn from its intercept position unless the track onto which the crane is to travel has been first properly aligned with the track on which the crane is situated. Specifically, my stop device comprises a first stop member pivotally mounted upon one beam and disposed adjacent one end thereof. This first stop member is adapted for movement about its pivot mounting. A second stop member is likewise pivotally mounted upon a second beam and disposed adjacent one end thereof. The second stop member is adapted for movement about its pivot mounting, and each of the two beams is adapted for disposal in an end to end relationship with the other.

Each of the stop members is so placed on its respective beam that a part thereof extends from the pivot mounting toward a flange of the beam along which a wheel or movable part of the carriage or crane rides. This part of the stop member is disposed in an intercept position relative to the flange of the beam so that it engages the wheel or movable part of the carriage and prevents the carriage from traveling to the end of the beam. Connected to one of the stop members is a means for swinging it about its pivot mounting out of the intercept position to a travel position whereat the carriage may travel to and beyond the end of its beam. The stop member with the swinging means connected thereto has an arm

which engages a pin joined to the other stop member and swings the other stop member from its intercept position when the swinging means moves the stop member with the arm about its pivot mounting from the intercept position to the travel position.

On at least one of the two beams is a lock means disposed to engage the stop member and prevent swinging thereof from the intercept position. The lock means is movable into and out of engagement with the stop member and is disposed adjacent the end of its beam. The other beam carries an unlock means positioned thereon to engage the lock means when the two beams are in an abutting end to end relationship. Engagement of the unlock means with the lock means moves the lock means out of engagement with the stop member whereby the stop members may be swung out of their intercept positions.

On one of the beams is a beam lock positioned to engage a part of the stop member disposed on the other beam when the stop member has been swung out of its intercept position into the travel position. This beam lock thus locks the stop member of the other beam in the travel position. It is movable into and out of engagement with the part of the stop member of the other beam and connected thereto is a means for moving the beam lock out of engagement with the part of the stop member of the other beam.

In the accompanying drawings I have shown a preferred embodiment of my invention in which:

30 Figure 1 is a side elevation view of my stop device mounted on two beams with the stop members in intercept position;

Figure 2 is a side elevation view of the stop device of Figure 1 showing the stop members in travel position;

35 Figure 3 is a plan view of the device of Figure 2;

Figure 4 is an end elevation view of my device on the left-hand beam viewing Figure 1;

Figure 5 is an end elevation view of my device on the right-hand beam viewing Figure 1; and

40 Figure 6 is an enlarged section view of the mounting for the stop members of my device.

Referring to Figures 1-6 inclusive, my stop device comprises a first stop member 1 pivotally mounted on an I-beam 2 and a second stop member 3 likewise pivotally mounted on a second I-beam 4. As shown, the I-beams are disposed in adjacent, aligned end to end relationship and on the beam 2 is a wheel assembly 5 of an overhead crane. The wheels 6 of the assembly 5 are disposed on the lower flange 7 of the beam 2 and travel therealong from the beam 2 to the lower flange 8 of the beam 4.

50 The first stop member is a pair of bars 9 and 10 mounted upon a pivot assembly 11 disposed in the web 12 of the beam 2. The pivot assembly has a spindle 13 positioned in a sleeve bearing 12a and rotatable therein with the sleeve bearing being disposed through the web 12 of the beam 2. The bars 9 and 10 straddle the web of the beam and are substantially parallel to each other as shown in Figure 3. One bar is affixed to each end of the spindle which rotates in the bearing 12a of the spindle 13. As shown in Figures 1 and 2, the pivot assembly is in the upper part of the web 12 and adjacent one end of the beam. Mounting of the bars upon the spindle is adjacent the upper end of each bar, viewing Figure 1, so that a part 14 of each bar normally extends downwardly toward the bottom flange 7 of the beam 2 and almost into engagement therewith.

Joined to the upper ends of the bars 9 and 10 is a head 15 made from two side pieces 16 and 17 each of which is joined to one of the two bars and is located at one side of the top flange 18 with a small clearance therebetween. The side pieces 16 and 17 extend beyond the end of the beam 2 and along a part of the sides of

beam 4 as shown in Figure 2 when the stop members 1 and 3 are swung into travel position. In other words, with the stop members in travel position, the side pieces 16 and 17 straddle the two beams 2 and 4 where the beams abut each other in an end-to-end relationship. Thereby, I maintain the two beams in end-to-end alignment and prevent them from moving apart and out of alignment, thus avoiding derailment of a crane. Extending between the two side pieces is a plate 19 which is above the top flange 18 and which is welded to the two side pieces.

The second stop member 3 is somewhat similar to the first and has the same pivot assembly 11 and two bars 20 and 21 similarly mounted. The two bars straddle the web 22 of the second beam and each has a part 23 which extends downwardly toward and almost into engagement with the bottom flange 8 of the second beam.

The stop members 1 and 3 are generally disposed as shown in Figure 1 and there are in an intercept position relative to the wheel assembly 5. In other words, the two bars 9 and 10 of the stop member 1 are located so that they engage the wheel assembly 5 should it travel towards the left-hand end of beam 2, viewing Figure 1. Thus the stop member 1 in the position shown in Figure 1, i.e., the intercept position, intercepts the wheel assembly and prevents the overhead crane of which the wheel assembly is a part from traveling beyond the lower end of bars 9 and 10 to the left, viewing Figure 1. The second stop member 3 functions in the same way.

Joined to the bar 20 of the second stop member 3 by spacers 24 and 25 is a pusher arm 26 which extends alongside the bar 20 and to one side of the top flange 27 of the beam 4 with a clearance therebetween.

Affixed to the lower end of the bar 20 of the second stop member is an eye-bolt 28 to which one end of a cable 29 is tied. The cable extends upwardly over a pulley (not shown) and thence down to floor level where it can be pulled to cause the second stop member to swing in a clockwise direction, viewing Figure 1, from the intercept position to a travel position, shown in Figure 2, where the part 23 extends in the direction of the top and bottom flanges of the beam 4. With the second stop member 3 in the travel position shown in Figure 2, it is withdrawn from interfering with travel of a wheel assembly or an overhead crane along the beam.

Swinging of the second stop member 3 in the clockwise direction on its spindle brings the pusher arm 26 into engagement with a pusher pin 30 joined to the side member 16 of the first stop member. Engagement of the pusher pin by the pusher arm causes the first stop member to swing in a counterclockwise arc from the intercept position to a travel position, i.e., the one shown in Figure 2, where the part 14 extends in the direction of the top and bottom flanges of the beam 2. Thus, by pulling on the cable 29, the stop device simultaneously brings both stop members 1 and 3 from the intercept positions to the travel positions.

To prevent inadvertent lifting of the stop members from their intercept positions to the travel position, a spindle lock 31 engages the spindle 13 and prevents the stop devices from rotation about their pivot assemblies. The two stop devices have identical spindle locks and therefore, description of one is a description of both. The spindle lock comprises a pin 32 movably mounted on one side of the web 12 of the beam 2 adjacent its abutting end and a coil spring 33 disposed in a housing 34 also on the same side of the web and joined thereto. The pin 32 has a shaft 35 which extends along the side of the web and a short distance ahead of the end of the web 12, as shown in Figure 1, where it engages a spring bumper 36 carried by the abutting beam. This bumper is mounted upon the web of the abutting beam opposite the end of the shaft 35. The pin 32 has a hook 37, one part of which slidably fits into a guideway 38 and extends

therethrough to a recess 39 in the spindle 13. When the spring bumper 36 does not engage the end of the shaft of the pin 32, the coil spring 33, connected to the shaft 35, urges the end of the hook into the recess of the spindle, thus preventing rotation of the spindle in its bearing and thereby precluding swinging of the stop member from the intercept position to the travel position.

This recess 39 is positioned on the spindle so that it is opposite the bore of the guideway 38 when the stop member is in its intercept position. Thus, when the end of the hook enters into the recess, the spindle cannot rotate and the stop members are locked in their intercept positions.

Engagement of the spring bumper 36 with the end of the shaft upon bringing two beams into abutting end to end relationship forces the pin 32 against the urging of the coil spring 33 to the left, viewing beam 4 in Figure 1, and thereby moves the end of the hook out of the recess. Thus the spindle and the stop member mounted thereon are free to rotate and be swung out of the intercept position. Accordingly, unless there is end to end alignment of the two beams, there cannot be an inadvertent movement of the stop members from intercept position to travel position.

When the two beams 2 and 4 are moved out of their abutting end to end relationship, the stop members fall by their own weight to the intercept position and the pins 32 no longer being subjected to the force of the spring bumper have their hooks moved into the recess 39 of the spindle by the coil spring 33 and thus lock the stop members in intercept position.

Mounted upon the top flange 27 of the beam 4 is a spring lock 40 which engages the plate 19 of the stop member 1 and maintains the stop member in travel position. The spring lock, of course, only engages the plate 19 when the arm 26 of the stop member 3 has contacted the pusher pin 30 and swung the stop member 1 into its travel position.

The spring lock comprises a plunger 41 having a beveled leading face 42 and being slidably disposed in a housing 43. Joined to one end of the plunger opposite the beveled face is an eye 44 to which is tied one end of a second cable 45. The second cable is used to pull the plunger to the left, viewing Figures 1 and 2, and out of engagement with the plate 19 of the stop member 1 so that the stop member is free to fall of its own weight into the intercept position.

A spring (not shown) in the housing 43 urges the plunger to the right and into engagement with the plate. The beveled face of the plunger permits the plate to easily pass downwardly into lock position whereat the beveled face end of the plunger extends above and over a part of the plate 19.

Extending laterally from the arm 26 is a clip 46 which is flat against the top flange 27 of the beam 4 when the stop member 3 is in its travel position. A lip 47 welded to the plate 19 of the stop member 1 fits down over the clip and thus provides a second lock for the stop members in travel position.

One or both of the pins 32 (Figure 1) carry an electrical contact 48 which engages a second electrical contact 49 attached to the beam 4 and connected to a conventional electric circuit (not shown) by wire 50 when the pin 32 is moved out of the recess 39 in the spindle 13.

One of the components of this electrical circuit is a light or buzzer (not shown) which is actuated when the two contacts engage one another, thus indicating that the stop members are unlocked.

My stop device has an outstanding safety feature, namely, that the stop members cannot be inadvertently raised from intercept position unless two beams are aligned in an abutting end to end relationship. Therefore, danger of overtravel of a crane on its track with a resulting wreck and/or dropping of the load, or even a falling of the crane from its track is eliminated. Thus

my device is highly useful for buildings in which cranes are transferred from one set of tracks to a second set of tracks, particularly through use of movable or floating beams.

While I have described a preferred embodiment of my invention, it is to be understood that it may be otherwise embodied within the scope of the appended claims.

I claim:

1. A carriage stop device mounted upon a beam along which a carriage travels to a second beam disposed in end to end relationship comprising a first stop member pivotally mounted upon one beam and disposed adjacent one end thereof, said first stop member being adapted for movement about its pivot mounting, a second stop member pivotally mounted upon the second beam and disposed adjacent one end thereof, said second stop member being adapted for movement about its pivot mounting, each of said stop members being so positioned on their respective beams that a part thereof extends from its pivot mounting toward a flange of the beam along which a wheel or movable part of said carriage travels and is there disposed in an intercept position to engage said wheel and prevent it from travel to the end of its beam, means connected to one of said stop members for swinging it about its pivot mounting out of the intercept position to a travel position whereat the carriage may travel from the end of the beam, said stop member with the swinging means connected thereto having an arm which engages a means affixed to the other stop member and swings it from its intercept position when the swinging means moves the stop member with the arm about its pivot mounting from the intercept position to the travel position thereby enabling the wheel of a carriage to travel from one beam to the other, lock means on at least one of said two beams and disposed thereon to engage the stop member and prevent swinging thereof from its intercept position, said lock means being movable into and out of engagement with said stop member and being so disposed adjacent the end of the beam that an unlock means carried by the other beam engages said lock means when the two beams are in an adjacent end to end alignment, and thus moves the lock means out of engagement with the stop member so that the stop member may be swung out of its intercept position.

2. The device of claim 1 characterized by beam lock means positioned on one of said two beams and adapted to engage a part of the stop member of the other beam when said stop member has been swung out of its intercept position into its travel position, said beam lock means being adapted to lock said stop member of the other beam in the travel position, said beam lock means being movable into and out of engagement with said part of the stop member, means connected to said beam lock means for moving it out of engagement with said part.

3. The device of claim 2 characterized by the stop member of the beam with the beam lock means having a clip extending therefrom, a projection member connected to the stop member of the other beam and positioned to engage said clip when the stop members are in the travel position.

4. The device of claim 1 characterized by said unlock means being a spring bumper connected to the web of its beam and being adapted to engage said lock means and move it out of engagement with its stop member.

5. The device of claim 1 characterized by one of said stop members having two side pieces which extend beyond the end of the beam mounting the stop member and which extend along a part of the sides of the other beam and straddle both beams when the stop members are in the travel position.

6. The device of claim 1 characterized by beam lock means positioned on one of said two beams and adapted to engage a part of the stop member of the other beam when said stop member has been swung out of its intercept position into its travel position, said beam lock means

being adapted to lock said stop member of the other beam in the travel position, said beam lock means being movable into and out of engagement with said part of the stop member, means connected to said beam lock

5 means for moving it out of engagement with said part, and one of said stop members having two side pieces which extend beyond the end of the beam mounting the stop member and which extend along a part of the sides of the other beam and straddle both beams when the stop members are in the travel position.

7. The device of claim 6 characterized by the stop member of the beam with the beam lock means having a clip extending therefrom, a projection member connected to the stop member of the other beam and positioned to engage said clip when the stop members are in travel position.

8. A carriage stop device mounted upon a beam along which a carriage travels to a second beam disposed in end to end relationship comprising a first stop member pivotally mounted upon one beam and disposed adjacent one end thereof, said first stop member being adapted for movement about its pivot mounting, a second stop member pivotally mounted upon the second beam and disposed adjacent one end thereof which end is adapted

25 to abut the end of the first beam, said second stop member being adapted for movement about its pivot mounting, each of said stop members being so positioned on their respective beams that a part thereof extends from its pivot mounting toward a flange of the beam along which

30 a wheel or movable part of said carriage travels and is there disposed in an intercept position to engage said wheel and prevent it from travel to the end of its beam, means connected to one of said stop members for swinging it about its pivot mounting out of the intercept position

35 to a travel position whereat the carriage may travel from the end of the beam, said stop member with the swinging means connected thereto having an arm which engages a means affixed to the other stop member and swings it from its intercept position when the swinging

40 means moves the stop member with the arm about its pivot mounting from the intercept position to the travel position, thereby enabling the wheel of a carriage to travel from one beam to the other, lock means on at least one of said two beams and disposed thereon to engage the stop member and prevent swinging thereof from its intercept position, said lock means being movable into and out of engagement with the stop member, unlock

45 means adapted to engage the lock means when the two beams are in an adjacent end to end alignment and move the lock means out of engagement with the stop member so that the stop member may be swung out of its intercept position.

9. The device of claim 8 characterized by one of said stop members having two side pieces which extend beyond the end of the beam mounting the stop member

55 and which extend along a part of the sides of the other beam and straddle both beams when the stop members are in the travel position.

10. The device of claim 8 characterized by beam lock means positioned on one of said two beams and adapted to engage a part of the stop member of the other beam when said stop member has been swung out of its intercept position into its travel position, said beam lock means being adapted to lock said stop member of the other beam in the travel position, said beam lock means being movable into and out of engagement with said part of the stop member, means connected to said beam lock means for moving it out of engagement with said part.

11. A carriage stop device mounted upon a beam along which a carriage travels to a second beam disposed in end to end relationship comprising a stop member pivotally mounted upon one beam and disposed adjacent one end thereof, said stop member being adapted for movement about its pivot mounting, an arm movably mounted upon the second beam disposed adjacent one

end thereof, said stop member being so positioned on its beam that a part thereof extends from its pivot mounting toward a flange of the beam along which a wheel or movable part of said carriage travels and which part is disposed in an intercept position to engage said wheel and prevent it from traveling to the end of its beam, means connected to the arm for moving it into engagement with a means affixed to the stop member and causing the stop member to swing from its intercept position to a travel position relative to the carriage whereat the carriage may travel from its beam to the other beam, lock means on the beam with the stop member and disposed thereon to engage the stop member and prevent it swinging from its intercept position, said lock means being movable into and out of engagement with the stop member and unlock means disposed to engage the lock means when the two beams are in adjacent end to end alignment, and move the lock means out of

engagement with the stop member so that the stop member may be swung out of its intercept position.

12. The stop device of claim 11 characterized by said stop member having two side pieces which extend beyond the end of the beam mounting the stop member and which extend along a part of the sides of the other beam and straddle both beams when the stop member is in the travel position.
